HAIR CURLER

N. William Norman, River Forest, Ill., assignor of
one-half to Edward A. Grange, Chicago, Ill.

Application May 24, 1939, Serial No. 275,511

6 Claims. (Cl. 132—33)

This invention relates particularly to a hair curling device adapted for home use to enable a woman to put a permanent curl in her hair unassisted. After human hair has been given what is known as a permanent wave, it continues to grow out and short hair appears which requires treatment before it is necessary to go to the expense and trouble of getting another complete permanent wave. The present device is designed to facilitate that operation.

The primary object of the invention is to provide a simple and relatively inexpensive device that can be operated easily and without danger.

A further object of the invention is to provide a simple winding spool and protective cover for enclosing the curl during a steaming operation.

Another object of the invention is to provide a tensioning device of simple construction which will assure the hair being properly stretched around the spool while the hair is being wound into a curl and will assist in holding the hair in tensioned condition during the heat treatment.

Another object of the invention is to provide a simple fastener for attaching the end of a hank of hair to the spool and providing a simple pivotal and rotatable connection between the cover-member and spool so that the device can easily be closed into winding position.

The invention is illustrated in a preferred embodiment in the accompanying drawing, in which—

Figure 1 is a side elevational view of the spool and cover device in closed position; Figure 2 is a similar view of the same device in opened position with the opened position of the snap fastener of the spool shown in dotted lines; Figure 3 is a broken elevational view of the heating unit which impales the knob and spool so as to heat the spool-member; Figure 4 is a plan view of the device shown in Figure 1; Figure 5 is a sectional view, taken as indicated at line 5 of Figure 4; Figure 6 is a broken longitudinal sectional view, taken as indicated at line 6 of Figure 4; Figure 7 is a sectional view, taken as indicated at line 7 of Figure 4; and Figure 8 is a sectional view, taken as indicated at line 8 of Figure 4.

In the embodiment illustrated, A designates a cover-member provided with a swivel member A'; B, a hollow metal spool provided with a snap fastener B', and a knob B²; and C, an electrical heating device adapted to fit into the spool B.

The cover-member A is preferably made of sheet metal and is of semi-circular, open-ended construction. The edges of the metal are turned

inwardly, as indicated at 9, so that no sharp edges are exposed. An ornamental bead 10 merely serves to make the device more rigid. As best shown in Figures 4 and 7, one edge of the cover-member is turned inwardly to provide a resilient lip 11 which acts as a tensioning device when hair is wound around the spool within the cover-member. It is essential to the successful operation of the process that the hair be tightly stretched around the spool and this tensioning device assures this and also that the hair will be distributed evenly along the spool. A pair of dome-shaped buttons 12 is struck inwardly in the cover-member so as to snap over the circular shank 13 of the knob B² and yieldingly hold the device in closed position. The knob also acts as a friction device to prevent the spool from unwinding. The swivel member A' comprises a pair of interfitting cup-shaped members 14 and 15 which serves as a journal for a head 16 of the spool B. The swivel member is hinged to the cover-member by means of a pivot 17.

The spool B comprises a tubular member having one end fixed to the head 16 by means of a pivot member 18 which also holds one end of the keeper B' in position. The keeper B' is equipped at its free end with a finger piece 19 and is adapted to snap around the spool B. The free end 30 of the spool is equipped with a heat insulating hollow knob B² which enables the spool to be rotated by hand. The knob has an opening communicating with the center of the spool so that the heating element C may be inserted there-through.

The heating element C is of known construction and has a metal tube 20 containing heating, resistance wire which is connected up through a heat insulating handle 21 to a current supply plug member 22. The device is designed, preferably, so that it will not attain a temperature in excess of 440° F.

It is a well known fact that the curls or waves are the result of flattening of the hair. If the hair be wound under tension while it is given the heat treatment, a flattening results. In the operation of the present device a protective clip (not shown) is snapped around a hank of hair close to the scalp so that the hair will not be pulled out of the scalp. The clip usually is covered with rubber and also helps to prevent steam and heat from contacting the scalp. Before winding the hair, a liquid is applied to the hair, which is a softening agent and opens up the hard scaly surface of the hair shaft, and then

the end of a hank of hair is clasped against the spool by means of the fastener B' and the device swung into the cover-member A. By rotating the knob B² the hair is stretched and drawn tightly around the spool as the result of co-operation with the tensioning device 11. The heating element C is then inserted into the device and held there for a period of from three to six minutes.

During the heating operation the cover forms a steam chamber which retains the heat and helps to provide an equal distribution of heat over the length of the hair to be curled. If desired, a notch may be provided on the heating element C so that it will set in position without being held manually during the heating operation. Preferably two of the curling devices are provided so that after the heat is turned off and the curl removed from the device, it may be allowed to cool while the user applies the other device to the next curl without loss of time. It may be noted that the hair is kept under tension during the heating operation by the tensioning device 11 and also by the knobs 12 bearing against the shank 13. Both of these devices resist unwinding until the operator is ready to open the device.

The foregoing detailed description has been given for clearness of understanding only, and no unnecessary limitations should be understood therefrom, for some modifications will be obvious to those skilled in the art.

I claim:

1. A hair curling device comprising: an arcuate cover-member; a spool pivotally and rotatably secured to said cover-member, said spool being hollow and adapted to receive a heating element; and tensioning-means on said cover-member yieldingly urged towards the spool to stretch hair being wound thereon.

40

2. A device as specified in claim 1, in which the spool is provided with a pivotally mounted spring catch adapted to snap around said spool and attach the end of a hank of hair thereto.

5 3. A device as specified in claim 1, in which the tensioning-means comprises a resilient lip formed integrally with said cover-member and disposed so as to press yieldingly on hair wound on said spool within the cover-member.

10 4. A hair curling device comprising: a semi-circular, open-ended, sheet metal cover-member having a resilient inwardly turned presser-arm; a swivel member hinged in one end of said cover-member; a metal spool-member having one end 15 journalled in said swivel member and provided at the other end with a finger knob, said spool being hollow to receive a heating element; means on said spool for attaching the end of a hank of hair thereto; and friction-means for 20 yieldingly resisting rotation of the spool within the cover-member.

5 5. A device as specified in claim 4, in which the friction-means comprises a pair of dome-shaped bosses struck into the cover-member so as to snap over a round shank of the finger knob and confine the spool within said cover-member.

25 6. In a hair curling device: a semi-circular, open-ended cover-member; a swivel member hinged within one end of said cover-member; a hollow metal spool-member having one end 30 journalled in said swivel member and provided at the other end with a heat insulating knob; a heating element of sufficient length to impale said knob and metal spool, and conduct heat to said spool; means on said spool for attaching a hank of hair thereto; and tensioning-means for 35 cooperating with the spool to stretch hair being wound thereon within the cover-member.

N. WILLIAM NORMAN.
